(57) **CLAIM**

The ornamental design for an automatic hay feeder, as shown and described.

DESCRIPTION

FIG. 1 is a side perspective view of an automatic hay feeder, showing my new design;
FIG. 2 is an open perspective view thereof;
FIG. 3 is a top view thereof;
FIG. 4 is a front view thereof;
FIG. 5 is a back view thereof;
FIG. 6 is a bottom view thereof;
FIG. 7 is a side view of FIG. 1;
FIG. 8 is an opposite side view of FIG. 7; and,
FIG. 9 is an exploded view of the automatic hay feeder. The broken line portion of FIGS. 1, 2, 4, 5, 7 and 9 is included to show environment that forms no part of the claimed design.

1 Claim, 6 Drawing Sheets
